MOTOR OPERATED DOOR CLOSING DEVICE

Walter P. Levon, Detroit, Mich., assignor to F. L. Jacobs Company, Detroit, Mich., a corporation of Michigan

Application February 6, 1942, Serial No. 429,784

4 Claims. (Cl. 268—3)

This invention relates to vehicles and in particular to door closing devices for vehicles.

One object of this invention is to provide a motor operated door closing device for yieldingly applying power to a vehicle door in order to close it.

Another object is to provide a vehicle door closing device actuated by an electric motor and including a mechanism so arranged that the motor stores up power in a spring before the force becomes sufficient to close the door, thereby permitting the use of a motor of small power for closing a very heavy door.

Another object is to provide an electrically operated door closing device for vehicle doors wherein an electric motor rotates a screw, the nut of which is connected to a spring which in turn is connected to the door, so that the motor will start rotating and store up power in the spring before the force becomes sufficient to close the door.

Another object is to provide a vehicle door closing device wherein the door is equipped with a hold-open door check, such that an electric motor stores up power in a spring, which power is transmitted to the door, preferably at a hinge thereof, and overcomes the resistance of the door check after a sufficient rotation of the motor, thereby releasing the door from the door check and closing the door.

Another object is to provide an electrical door closing device as set forth in the preceding objects wherein the device is mounted on the vehicle body adjacent the door, and is particularly adapted for closing the very large doors in certain types of motor vehicles, especially such doors as are held open by door checks at a distance beyond the reach of the driver while at the wheel.

Another object is to provide a door closing device as set forth in the preceding objects wherein the door may be opened and closed independently of the device and without interfering with the action thereof.

In the drawing:

Figure 1 is a horizontal section through a vehicle body and door immediately above a hinge thereof, showing a preferred embodiment of the door closing device of this invention partly in section and with the door in its closed position.

Figure 2 is a view similar to Figure 1, but with the door in its open position immediately after the start of the operation of the door closing device;

Figure 3 is a side elevation of the door closing device with the door in its open position, looking in the direction of the line 3—3 in Figure 2;

The closing of doors in modern vehicles, particularly motor vehicles, has raised a problem when the door is a large one, and is out of the

reach of the operator at the wheel. This is especially true where the door is equipped with the so-called "hold-open" type of door check such that when the door is swung open it remains in its open position until a sufficient force is applied to overcome the resistance of the door check. Where the door is wide and heavy, as in certain types of closed vehicles, the operator at the wheel cannot reach the door in order to close it. At the same time, the provision of an ordinary motor directly coupled to the door requires such an expenditure of force in overcoming the resistance of the door check as to necessitate the use of a comparatively large electric motor.

The door closing device of the present invention overcomes these difficulties by providing a small electric motor, the shaft of which drives a screw shaft having a nut connected to a coil spring. The opposite end of the coil spring is connected to some convenient point on the door, as on the door hinge, and at a distance from the pivot axis of the door. The motor itself is also preferably pivotally mounted.

As a consequence, when the door has been opened, and is held in its open position by the door check, the operator merely needs to energize the motor in order to close the door. When the motor is energized, it rotates the screw shaft, causing the nut to travel along the screw shaft. This elongates the spring, storing up energy therein until the force is sufficient to overcome the resistance of the door check. When this occurs the door closes quickly and efficiently. At the same time, moreover, the door may be opened or closed independently of the motor if the operator so desires.

Referring to the drawing in detail, Figures 1 and 3 show a vehicle body 10 having a door 11 pivotally mounted upon a hinge arm 12 which is provided with a pivot bolt 13 mounted on the bracket 14. The latter is secured as at 15 and 16 to the body panel 17 and door frame 18 respectively (Fig. 3). The bracket 14 is provided with bent portions 18a and 19 for facilitating its mounting in this manner, the body panel 17 being dished as at 20 to provide a convenient place of attachment.

The hinge arm 12 is secured as at 21 to the frame inside the door 11, and passes through an aperture 22 in the latter and through an enlarged aperture 23 in the door frame 18. At the location where the hinge arm 12 passes through the door frame 18 it is provided with a bend 24 equipped with a lug 25 having an aperture 26 for a spring anchorage, as hereinafter described.

Secured as at 27 to the body panel 17 is a motor bracket 28 having a base plate 29 and an outwardly extending bracket arm 30 of channel

cross-section. Extending over the outer end of the bracket arm 30 on opposite sides thereof is a motor support 31 of approximately U-shaped form. The bracket arm 30 and motor support 31 are provided with aligned apertures 32 for receiving a pivot bolt 33 pivotally connecting these elements to one another (Fig. 3). The motor support 31 is connected at its outer ends 34 to the end of the electric motor 35, as by the bolts 36.

The motor 35 is provided with a motor shaft 36 connected to a screw shaft 37 having a nut 38 threaded thereon. The screw shaft 37 is provided with a stop portion 39 between the motor shaft 36 and screw shaft 37. The nut 38 is provided with a peripheral spiral groove 40 having a portion of the convolutions of a coil spring mounted therein and anchored thereto at its end 42 (Fig. 2). The coil spring 41 surrounds the screw shaft 37 and the stop cap 43 secured as at 44 to the outer end thereof (Fig. 2). The opposite end 45 of the coil spring 41 passes through aperture 26 in the lug 25 and is anchored thereto by bending it in the form of a loop.

In the operation of the door closing device of the invention, let it be assumed that the door 11 has been swung open manually from the position of Figure 1 to that of Figure 2, where it is held by a conventional "hold-open" type of door check (not shown). To close the door, the operator merely closes a switch which connects the motor 35 in circuit with the storage battery (not shown). This switch is mounted in a position convenient for the operator, such as on the dash of the car.

When the motor 35 is thus energized, the rotation of its shaft 36 and the screw shaft 37 causes the nut 38 to travel along the screw shaft 37 toward the motor 35. This stretches the spring 41, but does not immediately move the door 11, due to the holding action of the door check. Thus a comparatively small motor 35 is able to store up a relatively large amount of energy in the spring 41. When the energy stored in the spring 41 is sufficient to overcome the resistance of the door check, the pull upon the hinge 12 at the lug 25 causes the door 11 to swing into its closed position (Fig. 1). The nut 38 continues to travel until it meets the stop 39 or until the switch is opened. The motor 35 is of the type which will permit temporary stalling without its becoming burnt out.

It will be evident that the operator can also open or close the door manually without employing the motor 35 and without the motor 35 interfering with the manually closing of the door or vice versa. The door closing device of this invention is thus a very helpful device, especially in vehicles equipped with very wide doors, since the operator can get into the car and seat himself behind the wheel, yet be able to close the door even though he cannot reach it directly.

While a specific embodiment of the invention has been described and illustrated, it will be understood that various modifications may be made within the scope of the appended claims without departing from the spirit of the invention.

What I claim is:

1. In a closing device for a vehicle door hingedly connected to the body of said vehicle and adapted to be manually opened, a motor rockably and swingingly secured to said vehicle body, said motor having an armature shaft, a coil spring

having one of its ends secured to one of the hinge members of said hinge connection, and screw-and-nut mechanism rocking and swinging with the motor interconnecting said motor and said coil spring and responsive to the operation of said motor for storing energy in said coil spring for closing said door after being manually opened, whereby said door may be closed without necessitating the occupant of said vehicle changing his position, said coil spring and screw-and-nut mechanism being maintained in straight-line driving relationship with said armature shaft throughout the swinging movement of said door.

2. In a closing device for a vehicle door hingedly connected to the body of said vehicle and adapted to be manually opened, a motor rockably and swingingly secured to said vehicle, said motor having an armature shaft aligned with said swinging connection, a spring device having one end secured to the hinge member carried by said door, a screw element coextensive with said armature shaft, a nut element thereon operatively interposed between said motor and the other end of said spring device, said screw element being connected to said motor to rock therewith and said nut element being directly connected to said spring device, and means responsive to the operation of said motor for causing said elements to move in a straight line relationship with said armature shaft and relatively to one another to deform said spring device and swing said door on its hinge connection to closed position after having been manually opened.

3. In a closing device for a vehicle door hingedly connected to the body of a vehicle and adapted to be manually opened, said hinge connection including a hinge strap carried by said vehicle door pivotally attached to said body, a motor rockably and swingingly secured to said vehicle, said motor having an armature shaft, a tension spring having one end secured to the hinge strap in spaced relation from the pivotal point of said hinge strap, a screw element coextensive with said armature shaft, a nut element threaded thereon operatively interconnected between the other end of said spring and said screw element, and said spring, screw element and nut element being responsive to the operation of said motor for causing said elements to move in a straight line driving relationship relatively to one another to tension said spring and to initiate swinging movement of said door about its hinge connection to close said door member after said door has been manually opened.

4. In a closing device for a vehicle door hingedly and pivotally connected to the body of a vehicle and adapted to be manually opened, a motor rockably secured to said vehicle body, said motor having an armature shaft aligned with said rockable connection between the motor and said vehicle body, a screw shaft connected to the armature shaft rockable with said motor, a traveling nut threaded on said screw shaft, and a spring encircling said screw shaft and connected at one end to said nut and at the other end directly to the hinge connection in spaced relation from the pivotal point thereof whereby rotation of said motor armature shaft causes said nut to travel on said screw shaft and tension said spring so as to swing said door on its hinge connection and close the door after the same has been manually opened.
